WILBUR F. CLARK, OF HAGAMAN'S MILLS, NEW YORK.

Letters Patent No. 84,170, dated November 17, 1868.

IMPROVED BRIDLE.

The Schedule referred to in these Letters Patent and making part of the same.

To all whom it may concern:

Be it known that I, WILBUR F. CLARK, of Haga-
man's Mills, in the county of Montgomery, and State
of New York, have invented new and useful Improve-
ments in Bridle-Bits; and I do hereby declare that the
following is a full, clear, and exact description thereof,
which will enable those skilled in the art to make and
use the same, reference being had to the accompanying
drawings, forming part of this specification, in which—

Figure 1 is a perspective view of my invention, when
on a horse.

Figure 2 is a detail view, showing the construction
of the bit.

Figure 3 is an enlarged detail view of the bit and its
accessory gear, when applied as in fig. 1.

Similar letters of reference indicate corresponding
parts.

The object of this invention is to provide a simple
bit and bridle for horses, which combines several ad-
vantageous features, each of which is herein duly set
forth.

The bit consists of a straight round bar, A, fitted
loosely in the side plates B, to which the headstall is
attached, in the usual manner.

The bar A is provided with pulleys a, having broad
flanges b, to keep the rein C on the pulleys.

The rein C is connected with a gag-runner, D, passing
from side to side over the horse's head, as shown.

E are martingales, and are joined to the gag-runner
and rein at the same point, which may be provided
with an ornamental button or plate, G, at the point of
junction on each side.

d are curved projections from the plates B, and serve
to keep the rein from getting off from the pulleys, and
also to check up the animal's head, in a manner to be
hereinafter described.

When the gag-runner is taken up short, so that the
junction G will not be brought into contact with the
bit, the bit will revolve when the reins are drawn by
the action of the pulleys, as will be obvious. This
revolving action is advantageous, as it will twist the

bit from between his teeth, in case he should seize it
and attempt to run. The sensation produced by the
revolving bit will also cause his attention to be drawn
from his own vicious desires or from any fright he may
experience.

When the gag-runner is let out, however, so that the
junction G aforesaid will come down to the bit, the latter
will not revolve, but will then act as an ordinary bit.

The arrangement of the gag-runner, rein, and mar-
tingales in the manner shown, causes them to act as a
curb upon the animal, and gives a purchase upon the
bit, as will be obvious.

The curved projections d, before alluded to, serve to
act as a check, in the following manner:

When the reins are slackened suddenly, after drawing
up the animal's head, the reins, falling down in a bight,
will jam against the lower corners of the parts d, and
thus hold his head up. This operation is illustrated
in fig. 3, the slackened rein being shown in blue color.

By slackening the reins in the usual manner, they
will slide over the pulleys when the horse puts down
his head to drink, by which it will be seen that a check-
rein will not be needed, and the horse may drink with-
out the driver getting from his seat.

When the reins are drawn in with ordinary tension,
the combined action of the gag-runner, reins, and mar-
tingales causes the animal to hold his head up, with
the neck bowed in a spirited style.

I claim as new, and desire to secure by Letters
Patent—

1. The revolving bit A, having pulleys a b, and work-
ing in the plates B, substantially as herein described.

2. The combination of the gag-runner D, rein C, and
martingales E, with the bit A, B B, a b, a b, substan-
tially as herein described.

The above specification of my invention signed by
me, this 1st day of August, 1868.

WILBUR F. CLARK.
